(57) **CLAIM**

The ornamental design for a light-weight portable folding chair, as shown and described.

DESCRIPTION

FIG. 1 is a front elevation view of the folding chair showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof;

FIG. 8 is a perspective showing the folding chair in semi-folded condition;

FIG. 9 is a top plan showing the folding chair in flat un-folded condition;

FIG. 10 is a perspective view of the folding chair in folded position for storage;

FIG. 11 is a front elevation view of the folding chair in folded position for storage; and,

FIG. 12 is a rear elevation view of the folding chair in folded position for storage.
